UNITED STATES PATENT OFFICE.

JOSEPH A. GERSON, OF HOUSTON, TEXAS.

FILING CABINET.

Application filed May 22, 1925. Serial No. 32,166.

This invention relates to new and useful improvements in a filing cabinet.

One object of the invention is to provide a filing cabinet specially designed to receive 5 tubes containing maps, blue prints and the like, which, on account of their size cannot be conveniently filed flat.

Another object of the invention is to provide a cabinet of the character described 10 having a surrounding and enclosing case wherein the cabinet proper is mounted, said cabinet being hinged, in the case and so formed and mounted as to render the filed articles readily accessible.

15 With the above and other objects in view the invention has particular relation to certain novel features of construction, operation and arrangement of parts, an example of which is given in this specification and 20 illustrated in the accompanying drawings, wherein:—

Figure 1 shows a front view of the cabinet, with the shutters open, shown partly in section.

25 Figure 2 shows a vertical sectional view.

Figure 3 shows a fragmentary vertical sectional view with the cabinet proper exposed for access to its contents and

30 Figure 4 shows a fragmentary transverse sectional view.

Referring now more particularly to the drawings, wherein like numerals of reference designate similar parts in each of the figures, the numeral 1 designates a surrounding case having the hollow base 2 and the top, back and sides 3, 4 and 5, 5. This case may be opened or closed by means of the usual shutters 6, 6.

Within the case the cabinet proper, designated as a whole by the numeral 7, is mounted.

This cabinet has the usual side walls and bottom. The bottom is designated by the numeral 8, and declines inwardly to provide a clearance between it and the top of the base 2. The cabinet 7 is hinged at its lower end to the back side of the base 2. The upper end of the cabinet 7 is open and declines forwardly. This cabinet has transverse partitions 9 from its lower to its upper end, spaced apart far enough to receive the tubes 10 between them, the tubes being of sufficient length to project up above the cabinet for ready access.

55 The cabinet is held in upright position, when not in use, by means of the flexible

side arms 11, 11, secured to the inside of the walls of the case and having engaging hooks 12, 12 at their outer ends adapted to engage in front of the cabinet as illustrated in Figures 1, 2 and 4. The cabinet also has the hand grips 13, 13 attached to its front wall so that when it is desired to gain access to the cabinet the hooks 12 are pressed back to release them and the top of the cabinet 60 pulled forwardly. It will swing forwardly on its hinges 14 until its bottom rests on the top of the base 2, assuming the position shown in Figure 3, thus varying the top of the cabinet clear of the case. When it is 65 moved back into the case it will contact with the beveled portions 15, of the hooks 12 and spread them, and its front wall will clear said hooks, when the cabinet is fully back to permit the hooks to engage in front of it. 70

Within the base 2 there is a transverse rod 16 with oppositely disposed coiled springs 17, 17, thereon. The inner ends of these springs are attached to said rod, and their outer ends are extending, forming arms 18, 18 which rest against the underside of the bottom 8 and assist in sustaining the cabinet. This arrangement prevents the cabinet from dropping forwardly too suddenly and also assists in moving it back into place. 75

What I claim is:—

1. A device of the character described including a surrounding case, a cabinet having side walls and a bottom, said bottom declining inwardly to provide a clearance 90 between it and the bottom of the case, said cabinet being hinged at its lower end to the back portion of the bottom of said case, the upper end of the cabinet being opened and declining forwardly and spaced transverse 95 partitions in the cabinet extending from the upper to the lower end thereof, and forming compartments of gradually increasing depth from front to rear.

2. A device of the character described including a surrounding case, a cabinet having side walls and a bottom, said bottom declining inwardly to provide a clearance between it and the bottom of the case, said cabinet being hinged at its lower end to the back portion of the bottom of said case, the upper end of the cabinet being opened and declining forwardly, spaced transverse partitions in the cabinet extending from the upper to the lower end thereof, flexible side arms secured to the inside walls of the case and having engaging hooks at the outer ends of 100 105 110

said arms adapted to engage in front of the cabinet to hold the same in upright position, a transverse rod extending through said case and coil springs attached to said rod and having extended free ends forming arms which rest against the bottom of said cabinet.

3. A device of the character described including a surrounding case, a cabinet having side walls and a bottom, said bottom declining inwardly to provide a clearance between it and the bottom of the case, said cabinet being hinged at its lower end to the back

portion of the bottom of said case, the upper end of the cabinet being opened and declining forwardly, spaced transverse partitions in the cabinet extending from the upper to the lower end thereof, an anchor rod, coil springs attached to said rod and extended forming yieldable arms which press against the bottom of the cabinet to assist in sustaining the same in upright position.

In testimony whereof I have signed my name to this specification.

JOSEPH A. GERSON.
